AUTOMATIC NUT GUN

Joseph Klopovic, Euclid, Ohio

Application August 15, 1944, Serial No. 549,525

7 Claims. (Cl. 81—125)

1

This invention relates to wrenches, and more particularly to magazine wrenches adapted for use in the rapid assembly or disassembly of parts secured by bolts or nuts associated with threaded studs and adapted to accommodate a plurality of such nuts.

An object of the present invention is to provide a tool of the character indicated, so constructed that in the application of a nut to a bolt or threaded stud the nut can be driven home and properly seated without regard to whether the bolt or stud projects beyond the outer face of the nut without any possibility of the bolt threading into the next adjacent nut in the magazine.

A further object of the invention is to provide a tool of the type indicated adapted to feed the supply of nuts forwardly in proper alignment and without possibility of jamming in the tool.

Further objects will appear in the course of the following detailed description.

The invention consists in the novel construction, arrangement, and combinations of parts hereinafter more particularly described and claimed.

One sheet of drawings accompanies this specification as part thereof, in which like reference characters indicate like parts throughout.

In the drawing:

Figure 1 is a longitudinal medial cross section through the improved tool;

Figure 2 is a fragmentary, enlarged scale, medial longitudinal cross section through the forward end of the tool, showing the forward nut in engagement with a bolt; and

Figure 3 is a transverse cross section taken on line 3—3 of Figure 1.

Referring to the drawing, the tool comprises a barrel 1 having one end closed by a cap 2 threaded or otherwise secured on the end of the barrel, the cap 2 being rigidly associated with a clutch member 3 of conventional design, the other member 4 of the clutch being adapted to be connected to a flexible rotary drive shaft by means of which the barrel 1 may be rotated on its longitudinal axis as desired.

A cylindrical hand clasp 25 is rotatably mounted on the forward end of the barrel and secured against longitudinal motion thereon as by a pin 28 having its inner end engaging an annular groove 27 in the barrel 1. From the foregoing, it will appear that the tool may be held by the operator by means of a freely rotatable sleeve or hand grip 25 adjacent its forward upper end and directed toward a bolt as desired, while the rota-

2

tion of the barrel can be readily controlled by the clutch member 3.

Adjacent the closed end of the barrel a restricted bore 6 is provided as by a suitable bushing 5 and in the bore 6 is slidably located the enlarged end 8 of a guide rod 9 axially positioned with respect to the barrel 1. A compression spring 10 is enclosed between the cap 2 and the enlarged head 8 operating to force the guide rod 9 toward the open end of the barrel 1.

Within the barrel 1 is positioned a spiral spring 31 circling the guide rod 9, the rear end of spring 31 bearing against bushing 5 and the forward end of the spring 31 bearing against a follower 15 30 having a hub 29 slideable on guide rod 9, this follower 30 being adapted to engage and press forwardly toward the open end of barrel 1 the stock of nuts within that barrel.

The nuts N are freely slideable upon the guide rod 9 and are retained in the barrel normally by balls 23 extending through radially spaced holes 24 adjacent the open end of the barrel and pressed inwardly by springs 22 seated in longitudinally extending slots 21 cut in the outer face of the barrel.

Normally the tool with a supply of nuts in the magazine occupies the position illustrated in Figure 1 with the balls 23 resiliently restraining the passage of the outermost nut.

30 To prevent the bolt or threaded stud from picking up more than the outermost nut, the guide rod 9 has its forward end provided with a bore in which are seated two spaced springs 12 having their rear ends secured to guide rod 9 as in slots 35 provided in a bushing 11. The forward free ends of the springs 12 are turned outwardly and formed as thread grippers 13—13 extending through radial holes 14—14 adjacent the forward end of the guide rod 9. The forward bore of the guide rod 40 is closed as by cap 15 screw threaded into the bore, this cap 15 having a central hole to slidably receive the stem 17 which has upon its rear end a cam member 18 and upon its forward end a bolt engaging face plate 19. A spiral spring 20 45 is interposed between the bolt engaging plate 19 and the forward end of the cap 15 tending normally to force the plate 19 forwardly and thus retract the cam 18 from between the spring members 12, thus permitting the thread grippers 50 13—13 to retract within the guide rod 9 and release the adjacent nut. In operation, as the bolt B threads through the outermost nut its end will contact the plate 19 and force the cam member 18 rearwardly, thus pressing the springs 65 12 apart and forcing the gripper members 13—13

into locking engagement with the threads of the next adjacent nut to the rear, thus locking said next adjacent nut with respect to the guide rod 9 and holding that nut and all other nuts in the magazine in position. When the plate 19 has been forced back to its limit, the outermost nut will be forced forwardly against the pressure of balls 23 until properly seated.

The inner bore of the barrel 1 will, of course, be shaped to conform with the contour of the nuts to be used and sized to permit the nuts sliding freely within the bore upon the guide rod 9. To facilitate the application of the tool in situations where it cannot be held in true alignment with the bolt or stud, the outer end of the bore of barrel 1 may be tapered slightly inwardly as indicated at 33 so as to permit a rocking of the rear-end of the outermost nut to facilitate its engagement with the bolt threads.

Various modifications in the mechanical form and construction of the various parts will readily suggest themselves to those skilled in the art but all within the scope of the present invention as claimed.

Having thus described my invention, I claim:

1. A magazine wrench comprising a barrel, means within the barrel to force nuts therein toward an open end of the barrel, means at said open end to resiliently retain the outermost nut and nut-gripping means within the barrel having an operating part normally positioned within the bore of the outermost nut arranged to be engaged by the end of a bolt threading through said outermost nut to actuate the nut gripping means to lock in position the next adjacent nut and occlude the bolt from said next adjacent nut.

2. The device of claim 1 in which the nut engaging means operated by the entering bolt comprises nut gripping members and the operating part thereof comprises a slidable member having a bolt engaging face and means for forcing the nut gripping members into engagement with the adjacent nut to lock the nut in position and limit the movement of the slidable member.

3. The device of claim 1 in which the nut engaging means operated by the entering bolt comprises oppositely disposed spring members secured by their rear-ends to a centering member and having their forward free ends outturned to engage the threads of an adjacent nut, associated with a slidable member having a cam shaped part adapted to force the free ends of the spring members apart and a bolt engaging face directed toward the open end of the barrel.

4. The device of claim 1 in which the nut engaging means operated by the entering bolt comprises oppositely disposed spring members secured

5 by their rear-ends to a centering member and having their forward free ends outturned to engage the threads of an adjacent nut, associated with a slidable member normally biased toward the open end of the barrel and having a cam shaped part adapted to force the free ends of the spring members apart and a bolt engaging face directed toward the open end of the barrel.

10 5. A magazine wrench comprising a barrel having an open end, an axially disposed guide member within the barrel on which a plurality of nuts can slide, a spring pressed follower slidable on said axial guide to engage the innermost nut, oppositely disposed spring fingers secured to a forward part of the axial guide, the forward ends of said fingers bent outwardly to form thread engaging parts, a member slidable in the forward end of the axial guide having a rearwardly directed cam part adapted to press said spring fingers apart and a forwardly directed bolt engaging face of a size to occlude an entering bolt from a nut opening.

15 6. A magazine wrench comprising a barrel having an open end, an axially disposed slidable guide member within the barrel on which nuts can slide, spring means biasing the guide toward the open end of the barrel, a spring pressed follower slidable on the guide biasing the nuts on the guide toward the open end of the barrel, nut engaging spring fingers carried by the guide, a member slidable in the forward end of the guide having a rearwardly directed cam portion adapted to operate the spring fingers into nut engaging position, said slidable member having a forwardly directed bolt engaging face with spring means biasing said slidable spring operating member toward the open end of the barrel.

20 7. A magazine wrench comprising an open ended barrel, means adjacent the open end to resiliently restrain the passage of nuts therethrough, a slidable axially disposed guide within the barrel, spring means biasing the guide toward the open end of the barrel, a follower slidable on the guide, spring means biasing the follower toward the open end of the barrel, spring fingers carried by the guide having their free forward ends outwardly bent to form thread engaging members, a slidable member mounted on the forward end of the guide formed with a rearwardly directed cam part adapted to wedge the spring fingers into nut engaging position and a forwardly directed bolt engaging face, spring means biasing the slidable member into nonoperative position, a hand grasp freely rotatable on the barrel and means for engaging the barrel with a source of rotary power.

JOSEPH KLOPOVIC.
